UNITED STATES PATENT OFFICE.

ERNEST HOPKINSON, OF NEW YORK, N. Y.

DESIGN FOR A TIRE.

50,202.

Specification for Design.

Patented Jan. 16, 1917.

Application filed December 24, 1915. Serial No. 68,589. Term of patent 14 years.

To all whom it may concern:

Be it known that I, ERNEST HOPKINSON, a citizen of the United States, residing at New York city, county of New York, and State of New York, have invented a new, original, and ornamental Design for Tires, of which the following is a specification, reference being had to the accompanying drawing,

forming part thereof, wherein the figure is a perspective view of a section of a tire showing my new design.

I claim:

The ornamental design for a tire as shown. Signed at New York, N. Y., this 22nd day of December, 1915.

ERNEST HOPKINSON.
